(57) **CLAIM**

The ornamental design for a collapsible kayak canopy, as shown and described.

DESCRIPTION

FIG. 1 is a perspective view of a collapsible kayak canopy according to the invention;

FIG. 2 is a front elevational view thereof;

FIG. 3 is a rear elevational view thereof;

FIG. 4 is a right side elevational view thereof as when looking left to right in FIG. 2;

FIG. 5 is a left side elevational view thereof as when looking right to left in FIG. 2;

FIG. 6 is a top plan view thereof;

FIG. 7 is a bottom plan view thereof;

FIG. 8 is a reduced perspective view of FIG. 1 showing the canopy mounted to a kayak shown in dotted lines; and,

FIG. 9 is the view of FIG. 8 showing the canopy in the collapsed position mounted to a kayak shown in dotted lines. The kayak appearing in dotted lines in FIGS. 8 and 9 is for environmental purposes only and does not form part of the claimed design.

The broken lines appearing on the canopy represent stitching and are part of the claimed design.
